UNITED STATES PATENT OFFICE.

NOBORU SEGAWA, OF ALVIN, TEXAS.

DESIGN FOR A TOY.

55,720.

Specification for Design.

Patented July 6, 1920.

Application filed April 27, 1918. Serial No. 281,265. Term of patent 14 years.

To all whom it may concern:

Be it known that I, NOBORU SEGAWA, a citizen of Japan, residing at Alvin, in the county of Brazoria and State of Texas, have invented a new, original, and ornamental Design for Toys, of which the following is a specification, reference being had to the accompanying drawing, forming a part thereof.

Figure 1 is a front elevation of the toy, and

Fig. 2 is a side elevation of the toy and showing my new design.

I claim:

The ornamental design for a toy, substantially as shown.

NOBORU SEGAWA.
